MACHINE FOR LACING SHOE UPPERS

Sidney J. Finn, Beverly, Mass., assignor to United
Shoe Machinery Corporation, Paterson, N. J., a
corporation of New Jersey

Application February 9, 1933, Serial No. 655,937

10 Claims. (Cl. 112—5)

The present invention relates to machines for lacing together the eyeleted quarters of shoe uppers before lasting and other operations. A well-known type of machine for performing the lacing operation is illustrated in the U. S. Patent to Enslin No. 1,030,573, granted June 25, 1912, and in the drawings annexed hereto the invention is illustrated as embodied in a machine of the type shown in that patent.

After the lacing operation on a shoe upper has been completed in the machine of the patent, the machine continues in motion preparatory to a new operation and forms a series of loops of lacing cord supported by a series of needles, and then comes to rest. The needles are provided with barbs forming hooks at their sides and opening towards their free ends to engage the cord when the cord is drawn towards the fixed ends of the needles. The loops are formed in part by a set of looper fingers engaging the cord at both sides of each needle. The thread, being secured to the machine at one end of the needle series, is laid in a straight line across the ends of the needles and within the open needle hooks. The looper fingers are mounted to move simultaneously against the thread in forming the loops so that the thread, for all loops except at the supply end of the series, is drawn from the supply through one or more sharp bends around the barbs of the needles nearer the supply. The greater the number of needles, corresponding to the number of eyelets in the uppers employed, the greater is the amount of resulting wear on the lacing cord, so that in some cases the cord may become strained or broken as the loops are being formed.

The principal object of the present invention is to reduce greatly the wear and strain during the formation of loops in the lacing cord used in a machine of this type, and to render the wear on any part of the cord substantially independent of the number of needles employed.

Another object of the invention is to improve the needle threading mechanism in a lacing machine of the type referred to, in order that the needles will be threaded with certainty before the looper fingers act to form the loops in the lacing cord.

In accordance with these objects, a feature of the present invention contemplates the provision in a lacing machine having a series of lace inserting needles, of means for relatively actuating the looper fingers and needles to form the loops one at a time and for so operating the machine that the supply of lacing cord for each needle

in being drawn from the supply is not substantially bent out of its path by the other needles. In the present embodiment of this feature of the invention, a series of independently actuatable looper fingers are provided and arranged to be actuated yieldingly against the cord in forming loops, thus preventing undue strain on those parts of the cord contained within the loops.

Another feature of the invention consists in providing a thread finger acting to engage positively the lacing cord with one or more of the needle barbs before the looper fingers begin to operate. In the present form of this feature, the thread finger moves the cord laterally against the sides of the first and second needles of the series to be threaded, so that the looper finger at the outside of the first needle of the series may be moved to form a right angle bent at one side of the first needle, even though the remaining needles have not yet been threaded.

The various features above referred to, as well as further features relating more or less to the preferred form and arrangement of devices employed in embodying the invention in the machine hereinafter described, will be understood from an inspection of the accompanying drawings, in which Fig. 1 is a plan view of the machine embodying the invention, the parts being shown in the positions which they occupy when the loops have been formed and are being held by the needles and looper fingers in position to be passed through the eyelet holes of the upper; Fig. 2 is a view in section taken through the machine along the line 2—2 of Fig. 1, but with the parts in a position taken after the machine has laced and released the upper of a shoe and the lacing cord is about to be threaded into the machine for a new operation; Fig. 3 is a plan view of the carrier for the looper needles and looper fingers; Fig. 4 is a similar view with the slide on which the looper fingers are mounted removed; Fig. 5 is a sectional view of the carrier shown in Fig. 3; Figs. 6, 7, and 8 are sectional views of a part of the looper finger mechanism and mounting in various successive positions; Fig. 9 is a diagrammatic plan view of the needles and portions of the looper fingers and other thread handling mechanism, partly in section, showing the position of the parts during the needle threading movement; Figs. 10, 11, and 12 are similar views showing successive positions corresponding to the positions of the loopers in Figs. 6, 7, and 8, respectively; and Fig. 13 is an end view of the needles and portions of the looper fingers in the positions shown in Fig. 9.

The machine illustrated in the drawings has the same general construction and mode of operation, except as hereinafter described, as the machine shown in the patent to Enslin, above referred to. The machine of the patent is intended to lace together by means of a lacing cord, the quarters of a shoe upper by passing the lacing cord through the eyelets formed in the uppers and fastening the ends of the cord together. In 10 operating upon an upper, the upper is positioned on the machine and the machine is set in motion for one complete cycle during which the upper is released. After the laced upper has been released, the machine continues in motion, re-threading the lacing parts to form a series of loops of the lacing cord and presenting the loops in position to be passed through the eyelet holes of the upper when the machine is restarted.

The machine comprises a series of lacing needles or spindles 2 equal in number to the number of pairs of eyelet holes which it is desired to lace, a plurality of looper fingers 4, each having an individually operative cord engaging portion, cooperating with the needles to form the loops in the lacing cord and to retain the loops in position until the eyelets on the shoe upper are impaled on the needles, a shuttle or cord feeding needle 6 acting to place the cord in position to be engaged by the needles and looper fingers, and to pass a portion of the cord through the loops after they have been engaged with the eyelet holes of the upper, a lacing severing means and a knot tying mechanism acting to tie the severed ends of the cord together.

The looper needles or spindles 2 of which there are four in the machine shown in the drawings, are mounted in a carrier 8, and the cooperating looper fingers are mounted in a slide 10 supported in guideways 12 on the carrier. The front end 40 of the carrier 8 is supported upon link connections for raising and lowering the carrier according to the movements of a cam lever 14 operated by a cam on a cam shaft 16. These connections differ somewhat from those shown in the machine of the patent and, for obtaining a greater mechanical advantage, comprise a bell crank lever 18 fulcrumed on a shaft 20 mounted in the frame of the machine, a link 22 connected between one end of the lever 18, and an arm 24 mounted to turn 50 about a fixed shaft 26. The carrier 8 is connected to the upper end of the link 22 by an adjustable link 28, so that the movements of the toggle comprising the link 22 and the lever 18 will be transferred to the carrier. The lever 18 is rotated about the shaft 20 by a second adjustable link 30 connected to a second arm of the lever 18 and the extreme end of the cam lever 14. The motion of the carrier throughout the cycle of movement of the machine is substantially the 60 same as that described in the patent. The rear end of the carrier 8 is pivotally supported upon the arms of a yoke 32 which is pivoted on a rod 34 and is rocked to give the carrier its forward and return movements by a cam on the cam shaft 16. Movements are imparted to the slide 10 which carries the looper fingers by means of a lever 35 which is connected with the slide by a link 36, and is provided with a roll engaging a cam groove formed in a cam on the cam shaft 16. The needles 2 are secured in spindles 38 rotatably mounted in blocks 40, and the blocks are mounted in guideways formed in the front of the carrier 8, so that the blocks may be adjusted to vary the spacings of the needles. The spindles 75 38 in which the lacing needles are secured are

arranged to be rotated to bring the hooks of the needles into position to receive the lacing cord, and to thereafter be turned into position to hold the loops so that the cord carrying needle 6 will pass through the loops.

In order to rotate the needles, crank arms 42 are secured to the rear ends of the spindles and are provided with pins 44 engaging a slot in a transverse bar 46. The bar is carried on the forward ends of two arms 48 and 50 connected to a shaft 52 rotatably mounted at one end in a boss 54 extending upwardly from the carrier 8, and at the other end in a side portion of the carrier. When the slide 10 is advanced and the looper fingers 4 are positioned adjacent the free ends of the needles, the cord carrying needle 6 is moved forward and back across the ends of the needles, and a length of cord is positioned to be engaged by the needles. Upon movement of the transverse bar 46 from its lowermost position to its raised position, as shown in Figs. 2 and 4, respectively, the needles are turned through an angle of 90° so that the loops, which at this time have been formed by the retraction of the looper fingers, are brought into a position for the passage of the cord needle through the loops.

The cord carrying needle 6 is secured to an arm of a needle carrying slide 56 which is mounted in guideways 58. The slide 56 is reciprocated by means of a cam on the cam shaft 16 engaging a roll on the rear end of a lever 60. The front end of the lever is provided with a segment 62 arranged to engage a pinion 64 which is connected with a gear 66 engaging a rack at one end of the needle slide 56.

The supply of lacing cord is led from the eye of the needle 6 through suitable guides 67 and a thread clamp 68. Before threading the needles 2, the cord carrying needle is first moved from the left of the machine, as shown in Fig. 1, across the lacing needles 2 to the right side of the machine. The free end of the lacing cord extending from the needle is then gripped at the right side of the machine, and the cord carrying needle is retracted, leaving a single length of thread extending in close proximity above the ends of the needles 2. The carrier 8 is raised by the link connections to the cam lever 14, causing the cord to be engaged with the needles, and the looper fingers are retracted to form loops in the cord. The needles are then rotated and the machine is brought to rest. Before starting the machine in operation the eyelets of a new upper are slipped over the threaded needles, so that upon movement of the cord carrying needle, the cord will be passed through the loops formed about the needles to prevent withdrawal of the loops from the upper after the upper has been released from the machine.

In the machine described in the patent above referred to, all of the looper fingers 4 are retracted simultaneously to form with the lacing needles loops of cord bent sharply about the ends of the needles, thus causing considerable tension and wear on the cord as it is drawn over the barbs of the needles from the supply.

According to the feature of the present invention, the looper fingers do not cause the cord after being threaded in the needles to be drawn from one loop to another, and the cord takes a substantially straight path from the cord carrying needle 6 to the needles as they are being looped. The looper fingers, in the machine embodying the invention, are mounted to move independently of each other and to this end with the ex-

ception of one are mounted upon rods 70 sliding in tubular members 72. The rods 70 have blocks 74 clamped to their forward ends by screws 16. The looper fingers are secured with 5 blocks 74 by screws 78 threaded in the blocks and engaging the looper fingers at their inner ends. The tubular members 72 are mounted upon the slide 10 by screws 80 passing through a slot 82 formed in the slide, being threaded at 10 their inner ends in lugs extending upwardly from the tubular members 72. The first looper finger, indicated at 84, at one end of the series of needles is not, however, mounted upon one of the rods 70, but is made fast directly to the slide 10 by a screw 86 which engages a block 87 on the 15 inner end of this looper finger (see Fig. 5). The looper fingers 4 are movable relatively to the slide 10, but are yieldingly held in an aligned position, as shown in Fig. 3, by coiled springs 88 surrounding the rods 70 within the tubular members 72, and being interposed between shoulders at the end of the tubular members 72 and blocks 90 attached to the inner ends of the rods 70. As 20 the slide 10 is retracted the springs 88 are compressed, but the looper fingers 4 are restrained from movement and are thus prevented from forming loops in the needles until after the looper finger 84 has withdrawn a length of thread across the first needle of the series.

30 In order to restrain the looper fingers 4 from movement with the slide 10, the blocks 90 are formed with downward projections 92 of successively increasing lengths extending through slots formed at the lower portions of the tubular members 72. These projections are engaged by a latch bar 94 formed with a pair of parallel arms pivotally mounted on a pair of studs 96 fixed in side portions of the carrier 8. After the slide 10 has been fully retracted, the latch bar is 35 moved downwardly, releasing the looper finger 4 next to the looper finger 84 which carries the projection 92 of shortest length. As the latch is moved further downwardly, it releases the remaining looper fingers successively by allowing the remaining projections 92 to escape and the looper fingers are all retracted one after another to the positions shown in Fig. 3 by the corresponding springs 88.

During the release of the looper fingers the 40 needles are held in the positions shown in Fig. 2 and while the looper finger 84 is being moved with the slide, the lacing cord is being drawn over the barb of the first looper needle 2 of the series and from the eye of the needle 6 in a substantially straight line. The next looper finger 4 is not operated until the slide has substantially completed its movement so that when it engages the cord in forming the loop around the second needle, the thread is no longer being drawn 45 through the first needle.

The positions of the parts during formation of the loops is more clearly shown in Figs. 9 to 12 inclusive, in which Fig. 9 shows the cord carrying needle 6 in a position to be engaged by the needles 2. The cord is shown extending in contact with a guide bar 98 which acts to hold the cord in proper position after the loops have been formed. Fig. 10 shows the position of the parts after the slide has retracted with the looper finger 84 while 50 the looper fingers 4 are held against movement. When the looper finger 4 adjacent the looper finger 84 is released by the latch 94, the cord is bent about and drawn against the second needle only, as shown in Fig. 11. When the third looper 55 finger has been released, the cord is drawn against

the third needle only, as shown in Fig. 12, and so on through the series until all of the needles have been completely threaded, the supply of cord being drawn only from the cord needle 6, and with a more regular movement than is possible when the looper fingers are all actuated simultaneously.

To cause the latch bar 94 to release the projections 92, a downwardly extending arm of the latch is connected by a link 100 with a cam actuated lever 102 carrying a cam roll engaging a cam on the cam shaft 16. The lever 102 is moved rearwardly, causing the latch bar 94 to be moved from the position shown in Fig. 6, downwardly until all of the projections 92 have been released. 10 The positions of the looper fingers 84 and 4 shown in this figure correspond to the positions shown diagrammatically in Fig. 10. After the latch releases the second looper finger, as shown in Fig. 7, causing the cord to take the position 20 shown in Fig. 11, there is no further movement of the cord through the hook of the second needle 2. After the third looper finger 4 has been released by the latch 94 into the position shown in Fig. 8, the cord is moved into the position shown in Fig. 12.

When the last looper finger has been released by the latch 94, the needles 2 are rotated approximately 90 degrees on their spindles 38 by a pin 104 carried by another arm extending from 30 the latch 94 and engaging the end of a slot 106 in a link 108 pivotally connected to an arm 110 extending from the hub of the arm 48. The arms 48 and 50 being attached to the shaft 52, raise the transverse bar 46 to rock the needles. 35 After an upper has been laced and released from the machine, the slide 10 and the latch 94 are returned to their original positions, and the needles are again rotated to the positions shown in Fig. 2.

When the slide 10 commences its retracting movement before the carrier 8 rises to its highest position, one or more of the looper fingers may reach the lacing cord before it has been engaged by the needles and, as a consequence, 45 one or more of the loops may be improperly formed. In order to avoid this result a thread finger 112 is provided to act between the first and second needles 2 of the series before the slide 10 carrying the looper fingers 4 begins to 50 retract. The cord is bent downwardly between the ends of the first two needles, as shown in Fig. 13, by the thread finger 112 in sufficient time to insure that the cord will be engaged in the eye of the first needle before the looper finger 55 84 reaches the cord.

The thread finger 112 is formed at the end of a rod 114 sliding in a block 116 at the front of the machine and is operated through a set of connections to a cam on the cam shaft 16. 60 The upper end of the rod 114 is connected by a link 118 to the upper side of the guideway 58. The lower end of the lever 120 is connected by a link 124 to a lever 126 fulcrumed on a shaft 128 carried by the frame of the machine. The lever 126 carries a cam roll 130 engaging an open cam on the cam shaft 16 and is maintained in engagement therewith by a coil spring 132 surrounding the shaft 128. One end of the spring 132 is attached to a pin 134 extending from the 70 lever 126 and the other end of the spring engages a pin 136 carried by a part of the machine frame so as to cause the cam roll 130 to follow the movements of the cam shaft.

The mechanism for gripping, severing and ty- 75

ing the ends of the cord and the operation of the other parts of the machine are the same as described in the patent hereinbefore referred to, to which reference may be had for a more complete description.

The nature and scope of the invention having been indicated, and a machine embodying the several features of the invention having been specifically described, what is claimed is:

- 10 1. A machine for lacing shoe uppers having, in combination, a plurality of needles, means for threading the needles with a lacing cord, a plurality of looper fingers, individual yielding means for actuating each looper finger, and a latch for restraining the looper fingers in inoperative position and for releasing them one at a time to form a series of loops in the lacing cord.
- 20 2. A machine for lacing shoe uppers having, in combination, a plurality of needles, means for threading the needles with a lacing cord, a slide, a plurality of looper fingers movably mounted on the slide, resilient means interposed between the slide and the looper fingers, means for actuating the slide to cause the looper fingers to form loops 25 in the cord between the needles, and a releasable latch to hold the looper fingers stationary while the slide is being actuated.
- 30 3. A machine for lacing shoe uppers having, in combination, a plurality of needles, means for threading the needles with a lacing cord, a slide, a plurality of looper fingers movably mounted on the slide, resilient means interposed between the slide and the looper fingers, means for actuating the slide to cause the looper fingers to form 35 loops in the cord between the needles, lugs extending from the looper fingers, and a latch arranged to engage the lugs and to release the looper fingers one at a time under the action of the resilient means.
- 40 4. A machine for lacing shoe uppers having, in combination, a plurality of rotatable needles, means for threading the needles with lacing cord, a slide, a plurality of looper fingers movably mounted on the slide, resilient means interposed 45 between the slide and the looper fingers, means for actuating the slide to cause the looper fingers to form loops in the cord between the needles, a releasable latch to hold the looper fingers stationary while the slide is being actuated, and 50 means for rotating the needles after the looper fingers have been released from the latch.
- 55 5. A machine for lacing shoe uppers having, in combination, a plurality of needles, means for threading the needles with a lacing cord, a slide, a looper finger fixed to the slide, a plurality of looper fingers movably mounted on the slide, resilient means interposed between the slide and the movable looper fingers, means for actuating 60 the slide to cause the looper fingers to form loops in the cord between the needles, and a releasable latch to hold the movable looper fingers stationary while the fixed looper finger moves with the slide.
- 65 6. A machine for lacing shoe uppers having, in combination, a plurality of needles, means for

threading the needles with a lacing cord, a slide, a looper finger fixed to the slide, resilient means interposed between the slide and the movable looper fingers, means for actuating the slide to cause the looper fingers to form loops in the cord between the needles, lugs extending from the other looper fingers, and a latch arranged to engage the lugs and to release the movable looper fingers one at a time under the action of the resilient means.

7. A machine for lacing shoe uppers having, in combination, a needle carrier, a plurality of barbed needles on the carrier, means for positioning a length of cord across the path of movement of the needles, a plurality of looper fingers, means for actuating the looper fingers to form loops in the cord between the needles, and a thread finger arranged to cause the cord to be engaged by the barbs of one or more of the needles before the looper fingers are actuated.

8. A machine for lacing shoe uppers having, in combination, a movable carrier, a plurality of barbed needles on the carrier, means for positioning a length of cord across the path of movement of the needles, means for moving the carrier to engage the cord in the needles, a plurality of looper fingers, means for actuating certain of the looper fingers to form loops in the cord between the needles before the carrier moving means is operated, and a thread finger arranged to cause the cord to be engaged by the barbs of one or more of the needles adjacent said certain of the looper fingers before any of said looper fingers are operated.

9. A machine for lacing shoe uppers having, in combination, a movable carrier, a plurality of barbed needles on the carrier, a cord carrying needle for positioning a length of cord across the path of movement of the needles, means for moving the carrier to engage the cord with the needles, a slide, a looper finger fixed to the slide, a plurality of looper fingers movably mounted on the slide, means for actuating the slide and the movable looper fingers at different times to form loops in the cord between the needles, and means for engaging the cord with the barb of a needle adjacent the fixed looper finger before the carrier moving means causes the cord to engage the other needles.

10. A machine for lacing shoe uppers having, in combination, a movable carrier, a plurality of barbed needles on the carrier, a cord carrying needles for positioning a length of cord across the path of movement of the needles, means for moving the carrier to engage the cord with the needles, a slide, a looper finger fixed to the slide, a plurality of looper fingers movably mounted on the slide, means for actuating the slide and the movable looper fingers at different times to draw lengths of cord through the needles, and a thread finger acting between two adjacent needles to engage the cord with the barbs of said needles before the needle moving means causes the cord to engage the other needles.

SIDNEY J. FINN. 65
